FRITZ ENSSLER, OF ROSELLE, NEW JERSEY.

REVERSIBLE ROTARY MOTOR.

1,278,126.

Specification of Letters Patent. Patented Sept. 10, 1918.

Application filed January 29, 1918. Serial No. 214,289.

To all whom it may concern:

Be it known that I, FRITZ ENSSLER, a subject of the Emperor of Germany, resident of Roselle, county of Union, and State of New Jersey, have invented certain new and useful Improvements in Reversible Rotary Motors, of which the following is a specification.

This invention relates to improvements in rotary motors or engines adapted to use fluids, gases or compressed air and which are reversible as to the direction of their rotation.

The principal object of the invention is to provide a compact form of motor which may be operated in either direction, and provided with two or more inlets and a single exhaust opening.

A further object of the invention is to provide a motor in which the impulsive effect of the current used is received upon elements pivoted to the central cylinder in such manner as to turn according to the direction of rotation desired.

These and other like objects are attained by the novel construction and combination of parts hereinafter described and shown in the accompanying drawings, forming a material part of this specification, and in which,

Figure 1 is a partial side elevational and vertical sectional view taken on line 1—1 of Fig. 2.

Fig. 2 is a vertical sectional view taken on another plane on line 2—2 of Fig. 1.

Fig. 3 is a side elevational view of the motor completely assembled.

Fig. 4 is a fragmental sectional view taken on line 4—4 of Fig. 1, and

Fig. 5 is a fragmental side elevational and sectional view of the same.

Throughout the several drawings, the numeral 10 indicates the base from which rises standards 11 the same being integrally connected with the body 12, and having one lateral finished surface 14, to which is attached a cover plate 15, by means of bolts 16, and screws 17, the former passing through raised lugs 18, formed with the body of the casing the cover having similar lugs 19, and a hub 20, formed to receive packing material 21, held by the nut 22, through which the shaft 23 passes.

The opposite end of the shaft is received in an extending hub 24, formed with the body 12, while the end extending through the cover plate is fitted with a driving wheel 25, for obvious purposes.

The casing contains a cylindrical bore 28 having therein a rotatably mounted solid disk 29, the same being held to the shaft 23, by the key 30. Circumjacent to the disk 29, are rings 33, between which a partition 31 is provided integral with one of the rings 33, which are held in position on the disk 29, by means of circular plates 35, which are clamped together by means of through bolts 36, the plates being recessed upon their outer sides, as are the adjacent surfaces of the cover 15 and body 12, thereby reducing the superficial area of the parts in contact.

The rings 33 are recessed the recesses having an arcuate formation at their ends and being disposed so as to form pockets 38 in staggered relation upon both sides of the partition 31, in which operate segmental shaped rocker buckets 40, pivoted upon the bolts 36, and having central hubs 41, movable in corresponding recesses 42 of the disk 29, the bucket ends being formed to suit the curved edges 38 of the recesses in the rings 33, and the outer surfaces of the buckets formed with a curved profile 43.

Extending from near the top of the casing 12, are angularly disposed hollow projections 45, containing ports or passages 46 and 48 respectively, opening into the casing and being separated longitudinally into equal parts by a partition wall 49. Revolvably mounted in the upper portion of the projections are rotatory valves 50, adapted to control the port openings and divert the propelling medium through either of the ports 46 or 48, the air or gases entering through the openings 52 of the screw threaded projections 53 from a supply source.

The valves 50 are operatively engaged by the caps 54, the stems 55 of the valves being fitted with nuts 56 at one end, the other extending ends 57 being squared and having fitted to them crank levers 58, both of the levers being pivotally engaged by a link 59, having near its center a pin 60 operating in a slot 62, formed longitudinally in a hand lever 63, pivoted on a bolt 64, fixed in a pro-

jection 65, formed with the casing 12, the lever having at its other end a handle 66 by means of which it may be operated.

On the opposite side of the lever 63, is an index finger 68, indicating the position of the valves as set to cause the motor to move forward, reverse, or remain stationary, the position of the finger 68, being indicated upon a sector 70, supported by a bracket 71, attached to the top of the casing 12.

Discharge or exhaust from the motor takes place through an extension 75, having a passage 76, terminating in a horizontal screw threaded projection 77, to which may be connected a pipe leading to the atmosphere.

The operation of the motor is as follows: The valves being set as indicated in Fig. 1, compressed air passes through, entering the inlets 53, passing through the valves 50, and is diverted thereby to the left side of the partition 49, and pass through the openings 46, impinging on the rear of the rocker buckets 40, causing them to move around the bore of the casing and the ring to rotate, and by reason of its engagement with the disk 29, actuate the shaft 23, and whatever may be attached to it.

The rocker buckets are uniformly disposed upon opposite sides of the disk, in staggered or off-set relation, and by reason of the two inlets, at least one of the buckets is always in position to receive an impulse thereby avoiding "dead centers" and the like.

When it is desired to reverse the motor the lever 66 is oscillated, thereby partially rotating the valves, delivering current to the rocker buckets, causing them to turn upon the bolts, 36 in the opposite direction, so as to receive current upon their opposite sides. It will be obvious that when the lever 66, is vertical the valves will be closed, permitting no current to enter the interior of the motor.

Having thus described my invention what

I claim as new and desire to secure by Letters Patent, is:—

1. In a rotary motor, the combination with a rigid hollow casing, a cover fitted thereto, and a shaft mounted partially in said casing and said cover, of a disk engaged with said shaft, annular plates on the sides of said disk, clamping elements engaging said plates to said disk, rings surrounding said disk through which said clamping elements pass, a partition between both rings integral with one of them, pockets formed in said rings in staggered relation upon opposite sides of said partition, a plurality of rocker shaped buckets pivotally mounted in said pockets, inlet ports, communicating with said casing, valves controlling said ports whereby an entering current may be diverted to either side of said ports and caused to impinge upon either end of said rocker buckets, and means for operating said valves.

2. In a reversible rotary motor, the combination with a casing having a central bore, a cover engaged therewith, and a shaft journalled in said cover and said casing, of a solid disk engaged on said shaft, a pair of annular plates on said shaft at the sides of said disk, rings surrounding said disk, pivot bolts connecting said plates and said rings, a partition between both rings integral with one of them, pockets formed in said rings in staggered relation upon opposite sides of said partition, a plurality of rocker buckets in said pockets, said buckets having a part operable in said pockets, one or more inlets to said casing, means formed in said inlets whereby an entering current may be diverted to impinge upon either end of said rocker buckets and a control means whereby said ring and disk may be turned in either direction.

In testimony whereof I have affixed my signature.

FRITZ ENSSLE.
